UNITED STATES PATENT OFFICE.

ADOLF B. HROMAS, OF ULYSSES, NEBRASKA.

FUEL-CONTROLLING DEVICE FOR MOTORS.

Application filed September 7, 1923. Serial No. 661,471.

To all whom it may concern:

Be it known that ADOLF B. HROMAS, a citizen of the United States, residing at Ulysses, in the county of Butler and State of Nebraska, has invented new and useful Improvements in Fuel-Controlling Devices for Motors, of which the following is a specification.

In a fuel controlling device for internal combustion motors, it is the purpose of the present invention to provide means for permitting an auxiliary supply of air to enter the gasoline tank to be carried to a point a substantial distance below the level of the gasoline and then conducted to the crank case and thence to the carburetor, additionally volatilizing the charge and hence producing a better fuel for combustion in the combustion chamber of the motor, thereby saving fuel and enabling the chauffeur to operate the automobile a greater distance on a predetermined amount of gasoline than heretofore obtained.

Another purpose is to provide means for conducting the air from the tank in such wise as to gather the waste that may pass around the piston and enter the crank case and conduct it into the carburetor, thereby producing a superior charge of fuel for combustion.

Still another purpose is to provide means for carrying the air from the crank case without interfering with the passage of oil into the crank case, that is, when a supply of oil is necessary.

It is to be understood that the particulars herein given are in no way limitative and that, while still keeping within the scope of the invention, any desired modifications of detail and desired proportions may be made in the apparatus according to the circumstances.

The invention comprises further features and combinations of parts to be hereinafter set forth, shown in the drawings and claimed.

In the drawings:

Figure 1 is a view showing the improved fuel controlling device as applied for use in connection with internal combustion motors.

Figure 2 is a sectional view through the gasoline tank, showing the means for permitting air to enter the tank and be con-

ducted to a point below the level of the gasoline and also showing the outlet for the air. 55

Figure 3 is a sectional view through the crank case, showing the means whereby the air and the fumes from the gasoline may be carried off from the crank case to the carburetor. 60

Figure 4 is a view at right angles to Figure 3 on line 4—4 thereof.

Referring to the drawings, 1 designates a conventional form of internal combustion motor, 2 denotes a conventional form of carburetor, 3 the tank and 4 the crank case. A cap 5 provided with a threaded extension 6 and an adjacent shoulder 7 is provided and is adapted to connect with the gasoline tank by engaging the extension 6 with the threads 70 in the opening of the tank.

The cap includes a second extension 8 which is reduced and which extends into the tank and terminates at a point a substantial distance below the level of the gasoline, 75 whereby a supply of air entering the lateral extension tube 9 may be conducted to a point below the level of the gasoline and closely adjacent the bottom of the tank so that it may again ascend through the body of gasoline and pass out through the cap 10 which also has a lateral extension tube 11. 80

The cap 10 has a threaded extension 12 and is provided with an annular shoulder 13. The extension 12 is threaded into the gasoline tank adjacent the end opposite the end having the cap 5. However, prior to disposing the caps 5 and 10 in position with their extensions 6 and 12 in threaded engagement with the openings in the wall of 90 the tank, suitable gaskets or washers 14 and 15 are first placed in surrounding positions with respect to the the extensions 6 and 12 so that the shoulders 7 and 13 will bear upon the gaskets and insure a tight fitting joint 95 between the extensions 6 and 12 and the edges of the openings as well as precluding the escape of any air about the shoulders 7 and 13.

The lateral extension tube 11 is connected 100 to a suitable metal flexible tube 16 which, in turn, connects to a tube 17 which is carried by a plate 18 which is mounted upon the transmission case. This plate 18 supports the tube 17 in such wise as to hold it in position whereby it may connect with the 105

crank case through the medium of a second metallic flexible tube 19. The flexible metallic tube 19 is communicably connected with the crank case for the purpose of conducting 5 the supply of air (which percolates through the body of gasoline in the tank) to the crank case.

An outlet air cup or tube 20 is engaged with one of the oil holes of the crank case, 10 there being a bolt 21 having a hook 22 at one end for holding the outlet cup in position. The upper end of the outlet cup has a lid or cover 23 for closing the cup to prevent dirt and other foreign matter from 15 entering the cup when filling the crank case with oil. A tubular extension 24 is provided. This extension 24 engages through the wall of the outlet cup 20 and is brazed thereto, as at 25. It will be noted that the 20 end portion of the lateral extension 24 is fitted transversely of the cup and has its lower portion cut away to permit the air passing upwardly through the outlet cup to pass out through the extension 24.

25 It will be noted that the part of the extension tube 24 opposite the cut away portion 26 deflects the oil toward either side when the cup is in the act of receiving oil, conducting it to the crank case. The bolt 30 21 engages through the wall of the extension tube 24 and is supplied with a nut 27 for adjusting the bolt in its proper position to retain the cup in the oil hole. The extension tube 24 connects with an elbow 28 by 35 means of a metallic flexible tube 29, said elbow being, in turn, properly and suitably connected to the carburetor.

In the operation of gasoline motors, it is 40 well known that there is a certain percentage of waste about the pistons during their operating movements and it is also well known that an auxiliary supply of air supplied with fumes from gasoline will act to additionally volatilize a charge and thereby save fuel and permit the vehicle to travel a greater distance on a predetermined supply of gasoline than has been heretofore obtained. Hence in the present device the air 45 is conducted through the body of the gaso-

line, gathering the fumes therefrom and 50 using the mixture for conduction into the carburetor.

The connections between the gasoline tank and the carburetor, as above described, are designed to be air-tight in order to prevent 55 any escape of the mixture which passes through the connections.

The invention having been set forth, what is claimed is:

1. In a fuel controlling device for internal 60 combustion motors, the combination with the crank case including a cup mounted in one of the oil holes whereby oil may be poured into the crank case, of a gasoline tank, means for conducting air below the 65 level of the gasoline in the tank whereby it may percolate through the body of gasoline, means for conducting the mixture of air and fumes from the gasoline to the crank case, means connecting the cup and the carburetor 70 for carrying the mixture of air, fumes from the gasoline and fumes from the oil from the crank case to the carburetor, and means extending into the cup for deflecting the oil 75 to either side when poured through the cup, thereby preventing the oil from entering the connection from the carburetor where it extends into the cup.

2. In a fuel controlling device for internal 80 combustion motors, the combination with the crank case thereof having an oil hole or opening therein for the application of oil to the case, and a carburetor, of a fuel connection between the carburetor and the crank case, said connection comprising a cup seated 85 in the oil hole, a removable cover closing the cup at the top, a tubular member effecting communication between the cup and the carburetor and extending laterally through the side walls of the cup and being cut away 90 within the cup below the plane of the horizontal diameter, and a clamping bolt engaging the extension within the cup and serving to clamp the latter in place in the oil hole.

In testimony whereof he affixes his signature.

ADOLF B. HROMAS.
